[57] **CLAIM**

The ornamental design for an adjustable length temple for spectacles, as shown and described.

DESCRIPTION

FIG. 1 is a front elevational view of an adjustable length temple for spectacles showing my new design;

FIG. 2 is a top plan view thereof;

FIG. 3 is a right side elevational view thereof;

FIG. 4 is a left side elevational view thereof;

FIG. 5 is a front elevational view thereof;

FIG. 6 is a front elevational view showing the temple adjusted to its shortest length;

FIG. 7 is a front elevational view showing the front guide detached for clarity of illustration;

FIG. 8 is an enlarged sectional end view taken along the line of 8—8 on FIG. 7;

FIG. 9 is a sectional view taken along the line of 9—9 on FIG. 7;

FIG. 10 is a sectional view taken along the line of 10—10 on FIG. 7;

FIG. 11 is a front elevational view with a spectacle frame shown in broken lines for illustrative purposes only and forming no part of the claimed design.
